OSCAR P. W. HANSON, OF SPOKANE, WASHINGTON.

RACK FOR THEATER-SEATS.

1,239,389.

Specification of Letters Patent.

Patented Sept. 4, 1917.

Application filed March 27, 1917. Serial No. 157,715.

To all whom it may concern:

Be it known that I, OSCAR P. W. HANSON, a citizen of the United States, residing at Spokane, in the county of Spokane and State of Washington, have invented new and useful Improvements in Racks for Theater-Seats, of which the following is a specification.

This invention relates to furniture, and more especially to hat and coat racks; and the object of the same is to produce an improved rack of this kind for attachment to the back of theater seats and the like for holding the hat and wraps of a person in the seat in the rear, and his cane or umbrella.

A special object of the invention is to so construct the rack that in its folded condition it is out of the way and not likely to catch in the garments of people who may be passing between the rows of seats.

The following specification sets forth details of construction, reference being had to the accompanying drawings wherein:—

25 Figure 1 is a perspective view of this device applied to the back of a theater seat or chair and in use, an umbrella being indicated in dotted lines as engaged with the hook.

30 Fig. 2 is a cross section on the line 2—2 of Fig. 1.

In the drawings I have used the letter C to designate the back of a seat or chair, being one of those which are placed in rows across a theater or other like auditorium, and of course it might be the back of a bench or pew as in a church. These rows of seats are placed close together, and so close in fact that it is with difficulty that a newcomer may pass transversely between the back of the seats in one row and the knees of spectators who may already be seated in the chairs of the next row. In some auditoriums it is even difficult for the newcomer to pass to his seat when those who have already arrived rise in their places. In any case the newcomer must pass by the wraps which may have been laid

over the backs of the seats in front or may be carried by attachments applied thereto, 50 with the result that some of these wraps are often swept from their racks, umbrellas are knocked down, and much confusion and discomfort follows. Efforts have hitherto been made to produce chair attachments or coat 55 and umbrella racks to meet the conditions named, and it is to this class of inventions that mine belongs.

Coming now to the details, this rack is made entirely of three pieces of wire. The 60 first is the support which comprises at its midlength a cross-bar 1, disposed horizontally and standing about two inches in rear of the back of the chair C, arms 2 bent from its ends, converging slightly toward each 65 other as seen in Fig. 2, and extending straight toward the back of the chair, loops or eyes 3 at the inner ends of these arms and through which screws S pass, legs 4 depending from said loops, and eyes 5 at the lower ends of 70 the legs formed at right angles to the plane of the loops 3 and the back of the chair, for a purpose yet to appear.

The second or swinging member comprises a cross-bar 11 whose ends are bent downward as at 12 and deflected slightly forward as at 13, and then carried straight downward for a considerable distance in side arms 14 which pass inside the cross-bar 1 of the support and continue below said cross-bar to eyes 15 at their lower ends standing in planes at right angles to and into engagement with the eyes 5 as shown. Attention is directed to the fact that the arms 14 are parallel and spaced a distance about equal 80 to that between the two pairs of inter-engaging eyes, and the gentle bends 13 cause the upper ends 14 of the arms and the entire cross-bar 11 to be deflected a little forward from the general plane of the two arms 14. 85 As seen in Fig. 2, the distance between the angles 6 and 7 where the cross-bar 1 of the support is united to its arms 2, is about the same as the distance between the arms 14 of the swinging member; whereas the distance 90 between the other ends of the arms 2

where they merge into the loops 3 is a little less, and each arm 2 is rounded or bent as at 8 into one side of its loop so that the arm 14 of the swinging member may pass 5 in behind it as this member is pressed toward the back of the chair C. The result is that when the swinging member is moved back against the chair, its side arms 14 spring a little as they travel along the converging arm 2 of the support, and finally 10 spring outward around the bends 8 to the position seen in Fig. 1, so that the entire swinging member is supported closely against the back of the chair and out of 15 the way. On the other hand, when it is desired to bring this member into position for use, the operator has but to grasp the cross-bar and pull it forcibly forward, with the result that each side arm is caused to 20 travel over the bend 8 and along the arm 2 of the support until it falls into the angle 6 or 7 and the parts stand as seen in Fig. 1. At this time the upper end of the swinging member is a considerable distance from the 25 chair farther than the cross-bar 1 stands from the chair, the latter distance being about two inches more or less, and therefore coats or wraps may be laid over the swinging member which forms as it were, an inclined shelf 30 for receiving them. The brim of the hat or cap may be passed over the cross-bar of the fixed support, and the crown of the same may project toward the knees of the wearer or owner and yet not to such an extent as to 35 interfere with them. Now when a new-comer arrives and desires to pass along the space between the chair-backs and the persons already sitting, the latter have but to lift out their hats or caps to clear a passage 40 sufficient for the new-comer to pass through. If the auditorium is built on a plan where the seats are extremely crowded, the original or first-comer may have to rise in his seat to permit the new-comer to pass, but this is 45 not the fault of the invention. Rather it is due to the poor spacing of the seats in the auditorium.

Another feature of my invention is its provision for supporting the cane or umbrella. At one of the angles as at 7 as shown, the wire of which the support is composed is given a twist to form an eye 20 and with this eye is engaged another, numbered 50 21, on the shank 22 of a hook 23, which latter might be of rather lighter wire than the remainder of the device. Attention is directed to the fact that the eye 20 of the support stands upright and in a plane at right angles to the back of the chair, whereas 55 the eye 21 of the hook stands upright and in a plane parallel with the back of the chair and the bill 23 of the hook projects from this eye in such direction that normally it hangs toward the chair-back and alongside

the interengaging eyes 5 and 15 above described. The result is that this hook normally hangs in a space no deeper than that occupied by the cross-bar 1 where it projects from the back of the chair, and its bill normally lies against the chair-back so that persons passing to and fro may not catch their clothing on the hook or in the eyes. When the hook is to be used, it is obviously swung up to the position seen in Fig. 1, and the cane or umbrella engaged with it and 75 stood on the floor. Thereafter when the new-comer passes by, the bill of the hook is yet directed toward the chair-back and held so by engagement with the umbrella, and the new-comer may not engage his 80 clothes thereon for this reason. The parts may be of any wire, but I would preferably treat them by nickelizing or japanning so that the entire device is tasteful in appearance and is an ornament rather than otherwise. The screws S may be any that are appropriate to the attachment.

What is claimed as new is:—

1. In a rack for theater seats and the like, the combination with a support comprising 90 a cross-bar, arms extending from its ends to the back of the seat and converging slightly toward each other in that direction, there formed into loops for attachment to said seat-back, legs continuing said loops and depending along the seat-back to points below the cross-bar, and eyes at the lower ends of the legs standing in planes at right angles to said seat-back; of a swinging member comprising a cross-bar at its upper end, parallel arms depending therefrom and separated a distance corresponding with the space between the outer ends of said arms, and eyes at the lower ends of the upright 95 arms standing in a plane parallel with the seat-back, and interengaged with the first-named eyes, substantially as described. 100

2. In a rack for theater seats and the like, the combination with a fixed support comprising 110 a horizontal cross-bar of wire bent at its ends into arms extending from the cross-bar toward the seat-back and converging slightly toward each other, each arm being bent outward gently at that end remote 115 from the cross-bar and formed into an eye, a screw passing through such eye into the chair-back, and other eyes outstanding from the chair-back below those first-named; of a swinging member of spring wire comprising 120 a cross-bar, upright side arms depending from its extremities and spaced from each other a distance to normally engage the angles between said first-named cross-bar and its arms but to spring over the bends of the latter, and eyes at the ends of the side arms of the swinging member interengaging the outstanding eyes on the 125 chair-back.

3. In a rack for theater seats and the like, the combination with a swinging member of inverted U-shape having eyes at the lower ends of its arms; of a supporting member of spring wire comprising a cross-bar bent at angles into arms, the remote ends of the latter bent into loops for attach-
ment to the chair-back and continued thence downwardly into legs, and the lower ends of the legs formed into out-standing eyes 10 interengaged with those first-named, for the purpose set forth.

In testimony whereof I affix my signature.
OSCAR P. W. HANSON.
